DESIGN FOR A BORDERING BLOCK

Maurice N. Lebecque, Groveland, Calif.

Application October 28, 1940, Serial No. 96,138

Term of patent 14 years

To all whom it may concern:

Be it known that I, Maurice N. Lebecque, a citizen of the United States, residing at Groveland, in the county of Tuolumne and State of California, have invented a new, original, and ornamental Design for a Bordering Block, of which the following is a specification, reference being had to the accompanying drawing, forming a part thereof.

The essential feature of my design resides in the specific arrangement of the large and small stones on the face of the block as shown.

I claim:

The ornamental design for a bordering block, as shown and described.

MAURICE N. LEBECQUE.
